LIQUID LEVEL RESPONSIVE FLOAT SUSPENSION

Norman Knecht, Philadelphia, Pa., assignor to Minneapolis-Honeywell Regulator Company, Minneapolis, Minn., a corporation of Delaware

Application January 28, 1953, Serial No. 333,730

3 Claims. (Cl. 248—317)

The present invention relates to liquid level responsive apparatus of the known type, shown, for example, in the Binckley Patent 1,966,537, of July 17, 1934. Apparatus of the type referred to comprises an elongated, vertically disposed displacer which is arranged so that the extent of upward movement is a small fraction of the rise in the liquid level producing the upward movement. In apparatus of the above mentioned type, the displacer is suspended from the free end of a generally horizontal arm, the other end of which is adapted to turn up and down about a horizontal axis as the displacer moves up and down in response to liquid level changes. The end of said arm is remote from the displacer and is attached to one end of a torque tube transverse to said arm. The second end of the torque tube is held against rotation, ordinarily by anchoring it to a stationary wall.

The general object of the present invention is to provide a novel and effective clip or connector for detachably connecting the displacer to the free end of the arm from which the displacer is suspended and facilitating its removal from the displacer chamber. The provision of a suitable connector through which the float is detachably suspended from the arm presents especial problems because of the character of the housing in which the displacer, arm, and torque tube are desirably mounted, and the relatively high pressure maintained in the housing. The displacer may well be two inches in diameter and a foot or so long, and is suspended in a vertical tubular housing section or displacer cage, with a detachable closure at its upper end and having an internal diameter of the order of three inches. The arm from which the displacer is suspended is mounted in a horizontal tubular housing section which has one end welded to the displacer cage, and the torque tube is mounted in a horizontal tubular section transverse to the first mentioned horizontal section.

A specific object of the present invention is to provide a suspension connection for a displacer normally locked to a supporting arm by means which can be easily unlocked, as by the use of an ordinary screw driver, when the closure at the upper end of the cage is removed, and can then be engaged by a hook drawn upward and out of the cage along with the displacer. The suspension device disclosed and claimed herein is desirably characterized by the small adverse effect on its operativeness of the corrosive actions to which such apparatus is ordinarily exposed. Another advantageous characteristic of the invention is the positive connections provided between the suspension device and the displacer and arm which it connects.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

2

Of the drawings:

Fig. 1 is an elevation partly in section through the float cage and an adjacent portion of the housing structure;

Fig. 2 is a reproduction on a larger scale of a portion of the apparatus shown in Fig. 1, with the connector body shown in section;

Fig. 3 is an elevation of the body portion of the connector shown in Figs. 1, 2 and 4 in a developed or flattened condition; and

Fig. 4 is an elevation of a locking part shown in Fig. 2 in a developed or flattened condition.

In the embodiment of the invention illustrated in the drawings, a displacer A is suspended in a vertical tubular housing or cage member B which has its upper end connected to a detachable closure element b. As shown, the housing structure includes lateral tubular branches or sections C and D, each secured at one end to the section B. An arm E is longitudinally disposed in the tubular section D and has its free end extending for a short distance into the displacer space surrounded by the cage B. The displacer A is suspended from the free end of the arm E by a clip or connector F as is hereinafter explained. The end of the arm E, remote from the member B, is connected to the inner end of a horizontal torque tube G. The latter is axially disposed in a tubular housing structure which is transverse to the housing section D and has one end rigidly connected to the latter. The second end of the last mentioned section is rigidly attached to a stationary, vertically disposed member I. The outer end of the torque tube G is anchored to the member I. Advantageously, the anchoring connection between the outer end of the torque tube G and member I comprises a splined connection J between the end of the torque tube G and a member K arranged for connection to the member I in a predetermined position. The splined connection between the tube G and the member K permits the latter to be secured to the torque tube in angular positions differing from one another by small increments. The anchoring arrangement just described is not claimed as novel by me, but is disclosed and claimed in the concurrently filed application for patent of William E. Bauer, Ser. No. 331,626, filed January 16, 1953.

As illustrated in Figs. 2, 3 and 4, the clip or connector F is in the form of a steel strip transversely bent to divide the strip into an upper vertical section 1, an intermediate inclined section 2, and a lower horizontal section 3. As seen in Fig. 2, the left side of the upper end of the intermediate section 2 intersects the upper section 1 along the line 4, and intersects the horizontal section 3 along the section line 5. In Fig. 3, the body portion F of the connector is shown in its flat or developed condition. As shown in Fig. 2, the inner end of the arm E extends through the upper portion of an aperture 6 in the strip F which is included in the vertical section 1 of the member F. The aperture 6 also includes a lower portion which extends into the inclined section 2 of the member F far enough so that its lower end is at the left of the arm E as seen in Fig. 3. This permits the member F, when not locked to the arm E, to be moved straight up into a position in which the end of the arm E is entirely out of the aperture 6.

Normally, however, the end of the arm E is locked in the upper portion of the aperture 6. The means for so locking the arm E includes a tooth-like portion 7 of the member F which normally extends downward through a vertical hole 8 in the arm E, as is clearly shown in Fig. 2. The tooth 7 is formed with a horizontal passage 9 which is at the underside of the rod E when the parts are arranged as shown in Fig. 2. The passage 9 normally receives a locking projection 10 of a bent metal spring strip 11. The strip 11 has an upper end portion parallel to and spot welded or otherwise attached to a

portion of the section 1 at some distance above the arm E. The portion of the strip 11 immediately above the pin 9 is bowed to the left away from the end of the arm E, as seen in Fig. 2. As shown, a thin metal strip 12 having an elongated upper portion alongside and welded or otherwise attached to the bowed portion of the spring strip 11, has its lower end portion reversely bent to form an uprising projection spaced away from the spring part 11 to the left.

To detachably connect the lower portion of the member F to the displacer A, the latter is formed with an axial stem 13 having an enlarged upper end 14. The stem 13 extends through an aperture 15 formed partly in the inclined intermediate section 2 and partly in the horizontal bottom section 3 of the member F. The width of the lower portion of the aperture 15 is a trifle greater than the diameter of the lower portion of the stem 13 but is less than the diameter of the enlarged upper end portion 16 of the stem. Thus it is not possible to separate the displacer A from the member F when the weight of the float is suspended from the horizontal portion of the member F. However, after being disconnected from the arm E and lowered relative to the stem 13 until the enlargement 14 is alongside the aperture portion 16, the member F may be disconnected from the displacer A by movement of said member to the left as seen in Fig. 2 until said member is at the left of the stem 13 and its enlargement 14 is at the right of the adjacent portion of the member F. Ordinarily the member F will not be disconnected from the displacer A until the latter has been withdrawn from the housing section or cage member B.

To remove the displacer A for inspection, cleaning or repair purposes, the pressure in the housing section is suitably reduced and the closure b is removed. A screw driver or like element may then be passed down into the tubular section B until its lower end is between the part 11 and the uprising extension 12. Thereafter the screw driver may be moved horizontally to move the projection 11 away from the arm E until the projection 10 is withdrawn from the opening 9 in the tooth 7. When the connector F is thus disconnected from the arm E, the displacer A may be drawn up out of the chamber B through the upper end of that chamber, as by means of a hook (not shown) extending through an opening 17 in the upper end of the section 1, as may be seen from Fig. 2.

As those skilled in the art will understand, the cage space or chamber surrounded by the wall B is ordinarily connected by equalizing connections to a vessel or liquid reservoir, one of which opens to said space at a level above the normal liquid level in said space, while the other opens to said space at a level which ordinarily is at least as low as the lower end of the displacer A. The tubular branches C may serve as the equalizing connections. When the apparatus is in operation, the globular portion 14 having a hemispherical surface on the lower

side is permitted to freely move in the lower portion of the aperture 15 without danger of becoming disengaged. Any surges in an upward direction are prevented from being applied to the arm E by the fact the stem 13 is free to move upwardly for a short distance. These factors all add to protecting the apparatus and making it universally useful.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. A suspension device comprising a vertical upper section, a horizontal lower section, and an inclined intermediate section, and formed with an upper aperture including a portion within said vertical section and a portion within said intermediate section, and formed with a portion of the vertical section of said device extending partially into said upper aperture, and formed with a lower aperture comprising a portion within said horizontal section and a portion within said inclined section, the portion of said lower aperture in said inclined section being of first cross sectional area, the portion of said lower aperture in said horizontal section being of a second cross sectional area less than said first cross sectional area, and the intermediate portion of said lower aperture between said first and second cross sectional areas forming a connecting channel whose width is less than any corresponding cross sectional dimension of said first or second cross sectional areas.

2. A device as claimed in claim 1 wherein the portion of the vertical section extending into the upper aperture has an opening in the lower portion thereof, and an elongated spring member fastened at one end to the upper vertical section above said aperture and extending outwardly and downwardly therefrom in the direction of said inclined portion, and having its other end extending back and adapted to project through said opening.

3. A device as defined in claim 2 wherein said spring has an upwardly extending hook member fastened thereto on the side thereof away from said vertical section, said hook providing a means for removing said other end of said spring from said opening.
